UNITED STATES PATENT OFFICE

OLDŘICH TUREK, OF PLZEN, CZECHOSLOVAKIA

BLASTING CARTRIDGE, PERCUSSION CAP, DETONATOR, DETONATING FUSE, AND THE
LIKE

No Drawing. Application filed September 11, 1928, Serial No. 305,324; and in Czechoslovakia October 13, 1927.

The invention relates to blasting cartridges, percussion caps, detonators, detonating fuses, special projectiles and the like, for the production of which use is made of 5 2,4,6-trinitro 1,3,5-triazidobenzene either alone or together with other explosives such as trinitrotoluene, tetryl, tetra-nitro-penta-erythrite and the like or admixtures such as powdered glass, potassium chlorate, barium 10 nitrate, antimony tri-sulphide and the like as described in my copending application Serial No. 305,323.

In blasting cartridges which were filled with 2,4,6-trinitro 1,3,5-triazidobenzene 15 together with other explosives or admixtures, it was found that the blasting cartridges which were filled with highly compressed 2,4,6-trinitro 1,3,5-triazidobenzene, upon which was rammed with considerable pressure a layer of lead azide weighing 0.05 to 0.2 gs. or another azide of heavy metals or their compounds, were superior in action and shattering power to all the blasting cartridges hitherto known. For the purpose of 20 protecting the layer of azide more satisfactorily, a protecting cap with a suitable aperture can be pressed on to the same simultaneously when ramming in the azide or another layer, one to two millimetres thick of 25 2,4,6-trinitro 1,3,5-triazidobenzene with a corresponding protective cap is applied with pressure to the azide layer.

The 2,4,6-trinitro 1,3,5-triazidobenzene necessary for carrying out the present invention is made by causing a suitable solution of 35 2,4,6-trichlor 1,3,5-trinitrobenzene to react upon a suitable solution of an alkali azide.

What I claim is:—

- 40 1. As a new explosive for use in blasting cartridges, percussion caps, detonators, detonating fuses, special projectiles and the like 2,4,6-trinitro, 1,3,5-tri-azido benzene in admixtures with an azide of heavy materials.
- 45 2. As a new explosive for use in blasting cartridges, percussion caps, detonators, detonating fuses, special projectiles and the like 2,4,6-tri-nitro, 1,3,5-tri-azido benzene in admixtures with a compressed layer of lead 50 azide.

3. As a new explosive for use in blasting cartridges, percussion caps, detonators, detonating fuses, special projectiles and the like 2,4,6-tri-nitro, 1,3,5-tri-azido benzene in admixtures with a compressed layer of lead 55 azide, weighing 0.05 to 0.2 grammes.

4. As a new explosive for use in blasting cartridges, percussion caps, detonators, detonating fuses, special projectiles and the like, a layer between one and two millimetres thick of 2,4,6-tri-nitro, 1,3,5-tri-azido benzene in admixtures with a compressed layer of lead azide, weighing 0.05 to 0.2 grammes.

In testimony whereof I have signed my 65 name to this specification.

OLDŘICH TUREK.
